Atkins.

UNITED STATES PATENT OFFICE

ALBERT M. WILKINS, OF CHICAGO, ILLINOIS, ASSIGNOR TO COOK ELECTRIC COMPANY,
OF CHICAGO, ILLINOIS, A CORPORATION OF ILLINOIS

DRAFT CONTROLLER

Application filed January 16, 1931. Serial No. 509,177.

My invention relates to electric draft controllers for heating systems designed to operate by any form of electrical means and controlled automatically by suitable means, which may be thermostatically or otherwise.

In the operation of heating systems provided with automatically-controlled electric draft controllers, independent control at the furnace of the draft and check dampers is desirable, so that during the firing of the furnace at least the check damper, if not both dampers, may be closed. After the firing of the furnace, automatic control of the draft controller over the dampers should again be resumed, so that the heating system will continue to operate automatically under the control of the room thermostat.

An object of my invention is to provide a draft controller which may automatically operate to open and close the check and draft dampers under the control of a thermostat or the like, but which will permit independent control of the dampers at the furnace for the purpose of being closed, when the furnace is fired and the fire door is opened, and which will resume automatic control over the dampers when the fire door is closed.

A further object of my invention is to provide a manually operated member adjacent to the fire door of the furnace, which, when moved manually, will close the check and draft dampers and permit the fire door of the furnace to be opened.

Specifically, these results are accomplished by allowing the damper doors to drop to closed position by the slack provided in the flexible connections, between the damper doors and the damper actuating arm of the controller, when the fire door is opened to fire the furnace. Closing of the fire door after the firing operation will take up the slack so that the damper doors will thereby be set in their normal position for continued automatic control by the draft controller.

I am aware that it is customary to make provision for closing the draft door or damper during firing of the furnace.

My invention, however, is fundamentally different in that the independent control over the draft door during firing is not obtained

by temporarily disconnecting the control of the motor of the draft controller from the damper actuating arm; in fact, the independent control has no relation to the operation of the draft controller, inasmuch as the draft controller may continue to operate under the influence of the room thermostat, thereby obviating any possibility of failing to resume control over the damper doors through failure of the disconnecting means to function properly.

In order to apprise those skilled in the art how to construct and practice my invention, I shall now describe a preferred embodiment thereof in connection with the accompanying drawing, in which:

Figure 1 is a view illustrating the front portion of a furnace or heater with the structure embodying my invention applied thereto;

Fig. 2 is an elevation of one side of the controller with the side of the cover removed; and,

Fig. 3 is a view of the rear wall of the controller illustrating certain circuit connections.

My invention, as embodied in the structure shown in the drawing, comprises an electric draft controller 1 which may be applied to various types of heaters or furnaces having the usual draft or air inlet 2 and a check damper 3.

In the drawing, I have illustrated a furnace, being designated 4, but it will be understood that in so far as the disclosure of my invention is concerned, the illustration is merely conventional, inasmuch as the invention is capable of wide application in this field and may be used to control elements other than the dampers of heaters.

The electric draft controller 1 is provided with a damper lever 5, mounted preferably in pivotal relation at the bottom of the controller, and having the ends of its arms perforated to permit attachment of suitable connections to the dampers 2 and 3. The left-hand arm of damper lever 5 may be connected to check damper 3 by a chain or other suitable connection 6, while the right-hand arm of damper lever 5 may be connected to draft or air inlet damper 2 by a chain or other suit-

able connection 7. Movement of damper lever 5 clockwise raises the left-hand arm to close check damper 3 and lowers the right-hand arm to open air inlet damper 2. Counterclockwise movement of damper lever 5 to the extreme opposite position closes air inlet damper 2 and opens check damper 3.

The particular illustration of the use to which my invention has been put may obviously be varied, including the relative arrangement or construction of the lever arms with respect to each other, without altering the operation of the controller or the flexible connections 6 and 7, to be presently described.

15 Any suitable actuating means may be provided as part of the electric draft controller for operating damper lever 5. It will be understood that while thermally operated element or vapor motor 9 is illustrated, any 20 suitable electrical mechanism or motor may be used instead in connection with the invention disclosed herein.

Thermal element 9 may comprise a rigid outer wall 10 and an expansible and contractible inner wall 14, suitably sealed together in hermetical relation at the lower end and fastened to base 12 of the housing of the controller. A tube 16, provided with a heat coil 11, is closed at its top and communicates 30 with the interior of a closed chamber provided by outer and inner walls 10 and 14. An actuating arm 17 extends through base 12 and into inner wall 14, being operably connected to the top of the inner wall.

35 A controller housing includes a vertical wall plate 21 carrying any suitable form of transformer 22, if so desired, and thermal blocks 23 and 24. Primary coil of transformer 22 is adapted to receive line wires 25 and 26, which wires are continued at 29 and 30, from the secondary coil of transformer 22 to terminal block 23. Wire 31, comprising a continuation of the circuit from wire 30 through terminal block 23, may connect to 40 a terminal band 32 (Fig. 2) surrounding and suitably attached at the upper end of tube 16. Heat coil 11 may be attached at its upper end to terminal band 32'. Wire 33 of the opposite side of secondary coil of transformer 22 45 forming a continuation of the circuit by electrically connecting to wire 29 at terminal block 23, connects to a terminal 35, on terminal block 24, and by means of a wire 38, to a thermostat 39. This thermostatic circuit is 50 completed by a wire 37, connecting to a terminal 34, also on terminal block 24, and then by a wire 46 leading from the opposite side of terminal 35 to a terminal band 32' surrounding and suitably attached at the lower end 55 of tube 16.

The closed chamber defined by the space between outer wall 10 and inner wall 14, as well as the interior of tube 16, is adapted to contain a volatile fluid, which, when heated, 60 will develop a pressure to move operating arm

17 downwardly. Such movement operates damper lever 5 clockwise, whereby to open draft or inlet damper 2 and to close check damper 3. This action normally occurs when the heating circuit is closed by the closing of room thermostat 39 upon lowering of the temperature in the room.

The volatile fluid will be heated by current flowing through heat coil 11 to develop heat at tube 16. The heat vaporizes and drives the volatile substance into the closed chamber of thermal element 9, whereby to expand the chamber and move actuating arm 17 downwardly. Coil 11 about tube 16 forms or establishes a heating zone. When the volatile substance is driven out of this heating zone into the closed chamber, further expansion thereof is checked. This movement of actuating arm 17 pivots damper lever 5 in a clockwise direction, as shown in Fig. 3, to open air inlet 2 and to close check damper 3. Air supplied to heater 4 by way of air inlet damper 2 supports combustion in the heater whereby the room temperature will rise and room thermostat 39 will open. Tube 16 then cools and the vapor condenses to allow the volatile substance to return into tube 16. The closed chamber will return to normal position and the upward movement of actuating arm 17 will rotate damper lever 5 counterclockwise whereby air inlet damper 2 is closed and check damper 3 is open.

95 During the firing of furnace 4, it may be desirable to close one or both dampers and check the draft. Temporarily disconnecting chains 6 and 7 to accomplish this result should not be permitted because it is possible that the attendant will forget to reconnect these chains to restore automatic control.

I provide means for closing either or both of damper doors 2 and 3 upon opening of the fire door 40. The arrangement includes a manually operated handle 41 suitably pivoted at 42 on heater 4 adjacent to door 40 to permit one end of this handle to overlie door 40, when in horizontal position, whereby to hold door 40 closed. At any suitable point, but preferably vertically thereover, a bracket 43 may be attached to a mounting 44. The horizontal leg of bracket 43 has openings therein to allow vertical movement of pins 45. Pins 45 are fixed to a horizontal bar 47 carrying pulleys 48 and 49 adjacent to its ends. Chains 6 and 7 may be entrained over pulleys 48 and 49, respectively. Vertical movement 100 of horizontal bar 47, being guided in such movement by pins 45, is provided by movement of a chain 50 connecting at its opposite end to fire door handle 41. Chain 50 may be supported in overhead relation by suitable 105 guide pulleys 51 and 52. Moving handle 41 to the position shown in Fig. 1 allows bar 47 to drop a short distance, thereby lowering pulleys 48 and 49. Lowering the pulleys 48 and 49 places slack in chains 6 and 7 so as to 110

allow doors 2 and 3 to close, it being understood that it is common practice in the art to support such doors on a horizontal axis so that they close by their own weight.

- 5 When handle 41 is moved to a horizontal position so that the right-hand end of the handle engages fire door 40 to prevent it from being opened, the bar 41 is raised to take up the slack in chains 6 and 7. Draft or air 10 inlet damper 2 and check damper 3 are again placed in their former position and automatic control by draft controller 1 over these dampers is again resumed.

From the foregoing description, it will be 15 obvious that a very simple form of draft controller is provided for automatically controlling the operation of the draft or air inlet damper 2 and check damper 3. Independent control of these dampers is obtained by opening 20 the fire door and automatic control will be resumed by closing the fire door. It is not necessary, therefore, to physically disconnect, or otherwise, the motor of the draft controller, nor is it necessary to provide mechanism permitting 25 the motor automatically to resume control after firing. The arrangement of the chains shown in the drawing is simple, inexpensive and positive in operation.

Without further elaboration, the foregoing 30 will so fully explain the gist of my invention, that others may, by applying current knowledge, readily adopt the same for use under varying conditions of service, without eliminating certain features, which may 35 properly be said to constitute the essential items of novelty involved, which items are intended to be defined and secured to me by the following claims.

I claim:

- 40 1. An automatic control for operating the draft damper and check damper of a furnace comprising, in combination, a motor, a thermostat responsive to temperature variations for controlling the operation of the motor, a 45 damper actuating member adapted to be operated by the motor to control the dampers, flexible connections between the damper actuating member and the dampers, a support mounted substantially above the motor and the dampers, a member mounted for reciprocal movement in said support, pulleys upon the reciprocal member over which the flexible connections extend from the dampers to the damper actuating member, and a flexible connection for holding the reciprocal member in the support adapted to raise and lower the same depending upon the position of the fire door of the furnace.

50 2. An automatic control for operating the draft damper and the check damper of a furnace comprising, in combination, a damper controller, a thermostat for controlling the operation of the damper controller, an apertured U-bracket rigidly supported above the 55 dampers and the damper controller, a bar,

60 pulleys on said bar, pins on said bar movable in the apertures of the U-bracket, a flexible connection holding the pins in the apertures, other flexible connections extending over the pulleys from the dampers to the damper controller, and a connection between the first 65 said flexible connection and the fire door of the furnace whereby opening of the fire door causes the first said flexible connection to lower the pins in the apertures whereby to lower the bar and temporarily to disconnect the dampers from the control of the damper controller.

70 3. An automatic control for operating the draft damper and check damper of a furnace comprising, in combination, a motor, a thermostat responsive to temperature variations for controlling the operation of the motor, a damper actuating member adapted to be operated by the motor to control the dampers, flexible connections between the damper actuating member and the dampers, a support mounted substantially above the motor and the dampers, a member mounted for reciprocal movement in said support, pulleys upon the reciprocal member over which the flexible connections extend from the dampers to the damper actuating member, and a flexible connection for holding the reciprocal member in the support adapted to raise and lower the same.

75 4. An automatic control for operating one or more dampers of a furnace comprising, in combination, a support mounted substantially above said dampers, a member mounted for reciprocal movement in said support, connections leading to said dampers from said reciprocal member, and means for raising and lowering said reciprocal member in said support to open and close said dampers.

80 In witness whereof, I have hereunto subscribed my name.

ALBERT M. WILKINS.
